No. 892,068.

PATENTED JUNE 30, 1908.

F. F. MAIN.
WRITING MACHINE.
APPLICATION FILED JULY 1, 1907.

UNITED STATES PATENT OFFICE.

FRED F. MAIN, OF COLUMBUS, OHIO.

WRITING-MACHINE.

No. 892,068.

Specification of Letters Patent. Patented June 30, 1908.

Application filed July 1, 1907. Serial No. 381,784.

To all whom it may concern:

Be it known that I, FRED F. MAIN, a citizen of the United States, residing at Columbus, in the county of Franklin and State of Ohio, have invented certain new and useful Improvements in Writing-Machines, of which the following is a specification.

The object of my invention is to return the carriage to the beginning of a new line, from 10 any point of its travel, with no greater expenditure of force than is required to press any other key.

The action of the several parts will be easily understood from the simple drawing, 15 attached to and forming a part of this specification.

Figure 1 shows the top and corner of a typewriter with my invention applied. Fig. 2 shows the operating position of the three-way valve. Fig. 3 shows the three-way valve with lever to operate manually.

The sections of the valve are made on line 00, Fig. 3, in the direction of the arrow.

In Fig. 1 a small pulley or grooved wheel 1 is attached by means of bracket 2 to the right side of the typewriter and in line with carriage return and line spacing lever 3. Attached to carriage return and line spacing lever 3 is a flexible cord 4, which passes over 25 grooved wheel 1, down the side of the machine below the table or desk, and is connected to a piston 7, fitting cylinder 6. The piston is held normally at the top of the cylinder 6 by a long, coiled spring attached 30 to bracket 2 and piston 7. This leaves the flexible cord 4 slack, and the carriage free to make any of its normal movements.

Iron core 9 is suspended by a spring 10 in upper part of solenoid 8 and is connected to 40 valve operating lever 17 by flexible cord 11. Iron core 13, spring 14, flexible cord 15, valve operating lever 16 and solenoid 12 are similarly connected. Valve 18 is a simple three-way valve with lever operating arm 16, 17 45 bent as shown. Arm 17 as before stated is connected to core 9 by flexible cord 11. Arm 16 is connected to core 13 by flexible cord 15. Air-tight connection is made by pipe 20 from bottom of cylinder 6 to valve 18, by pipe 21 50 from valve 18 to air-exhausted chamber 22. Solenoid 8 is connected with source of electricity 23 and circuit closing key 24, which may be placed on the typewriter, on the table, on the floor, or any place convenient to 55 the operator. Solenoid 12 is connected to

source of electricity 23 and to circuit closing means 28 and 29.

An extension 28 of conducting material is placed on the carriage and rod 29 of conducting material, suitably supported, is so placed in reference to extension 28 that the forward movement of the carriage necessary to engage the escapement, after the return of the carriage, will break the electrical connection between extension 28 and rod 29. 65

In the mechanical operation of valve 18, a key and plunger 31 is suitably placed and pivoted to arm 17. Arm 16 is connected to spring 32 which holds the valve operating lever in normal position as shown in Fig. 3. 70

The operation of my device is as follows: Key 24 is depressed whenever it is desired to have the carriage returned to the beginning of the line, this closes the circuit between solenoid 8 and source of electricity 23 thus 75 energizing solenoid 8, whose core 9 is quickly drawn into it, giving a sudden jerk to the valve operating lever 17 which opens the valve as shown in Fig. 2, so that the air from cylinder 6 may rush into the exhausted 80 chamber 22. This quickly draws piston 7 to the bottom of the cylinder 6 and by means of attached cord 4 passing over pulley 1 to the carriage return lever 3, quickly returns the carriage to the beginning of the 85 new line at the same time advancing the paper. When key 24 is released the solenoid 8 ceases to attract its core 9, which is quickly returned by spring 10, leaving cord 11 in a slack position as in Fig. 2. 90

When the carriage makes the full return movement the extension 28 makes contact with rod 29 which, through wires 27 and 30 causes solenoid 12 to be energized so that core 13 is quickly drawn into solenoid 12 and 95 by means of flexible cord 15 gives a sudden jerk to operating lever 16, closing the valve 18 connects cylinder 6, through pipe 20, to outside air at vent 19 Fig. 1. Piston 7 is thus instantly released and returned by spring 5 100 to the top of cylinder 6 so that it is no hindrance to the movements of the carriage. The small forward movement of any carriage when brought fully home, until the escapement takes the strain, is sufficient to break 105 the contact between extension 28 and rod 29.

I wish it distinctly understood that I do not confine myself to electrical means only for operating the valve, but also use a direct-connected mechanical means as shown in 110

Fig. 3. The key 31 is depressed and held till the carriage has returned to the required position, when spring 32 closes the valve and opens vent 19. The key whether directly connected or used to control electrical devices may be placed upon the typewriter, typewriter stand or on the floor to be touched by the operator's foot.

What I claim and desire to secure by Letters Patent is:

1. In combination with a typewriter and the carriage thereof, having a line spacing lever, a cylinder having an open outer end, a piston in the cylinder, a spring for supporting said piston extending through said open end of the cylinder, a connection between said piston and said lever also extending through said open end of the cylinder, a chamber having a vacuum maintained therein, a connection between the lower end of said cylinder and said chamber, a valve in said last named connection and means for operating said valve whereby when in one position it establishes communication between said chamber and cylinder and when in another position it closes said communication between the chamber and cylinder.
2. In combination with a typewriter and the carriage thereof having a line spacing

lever, a chamber having a vacuum maintained therein, a piston cylinder, a spring supported piston in said cylinder, means for connecting said piston and lever, a pipe connection between said chamber and the base of the cylinder, a valve in said pipe to establish and cut off communication between said cylinder and piston, oppositely disposed arms carried by said valve, and means connected to each arm for operating the same in opposite directions.

3. In combination with a typewriter and the carriage thereof having a line spacing lever, a chamber having a vacuum maintained therein, a piston cylinder, a spring supported piston in said cylinder, means for connecting said piston and lever, a pipe connection between said chamber and the base of the cylinder, a valve in said pipe to establish and cut off communication between said cylinder and piston, oppositely disposed arms carried by said valve, a spring mounted core having connection with each of said arms, a solenoid for each core, and means for enabling said solenoids to be energized.
